DESIGN FOR A SMOKING STAND

Albert C. Grunwald, River Forest, Ill., assignor to Precision Metal Workers, Chicago, Ill., a corporation of Illinois

Application April 21, 1937, Serial No. 68,903

Term of patent 7 years

To all whom it may concern:

Be it known that I, Albert C. Grunwald, a citizen of the United States, resident at River Forest, in the county of Cook and State of Illinois, have invented a new, original, and ornamental Design for a Smoking Stand, of which the following is a specification, reference being had to the accompanying drawing, forming part thereof.

Fig. 1 is a side elevational view of a smoking stand embodying my new design;

Fig. 2 is another side elevational view taken at right angles to the view of Fig. 1;

Fig. 3 is a top plan view of said smoking stand;
Fig. 4 is a view taken on the line 4—4 of Fig.
1 and looking upwardly as indicated by the arrows; and

Fig. 5 is a view taken on the line 5—5 of Fig. 1
and looking downwardly as indicated by the arrows.

I claim:

The ornamental design for a smoking stand,
as shown.

ALBERT C. GRUNWALD.
